UNITED STATES PATENT OFFICE.

JOHN G. MEYER, OF BALTIMORE, MARYLAND.

GAS WATER RADIATOR.

1,402,522.

Specification of Letters Patent.

Patented Jan. 3, 1922.

Application filed February 26, 1921. Serial No. 448,215.

To all whom it may concern:

Be it known that I, JOHN G. MEYER, a citizen of the United States, residing at Baltimore, in the State of Maryland, have invented certain new and useful Improvements in Gas Water Radiators, of which the following is a specification.

This invention relates to improvements in gas water radiators and has for its object to 10 provide a simple, cheap and efficient means for heating water supplied to the radiator or radiators as well as water to the fixtures in the house.

The invention consists of the novel construction and arrangement of the parts and combination of parts hereinafter more fully set forth in the following specification and pointed out in detail in the appended claim.

Referring to the accompanying drawing: 20 Figure 1 is an elevation of a radiator having my invention applied thereto.

Figure 2 is an end view of Fig. 1.

Figure 3 is a top plan view of Fig. 1.

Referring to the accompanying drawing, 25 forming part of this specification and in which like reference numerals designate like parts throughout the several views thereof, 1 designates a casing arranged in the center of the radiator sections 2 which are connected by the pipes 3 at the top to the union 4 and by the pipes 5 at the bottom to the union 6. The said union 4 is connected to the pipe 7 which in turn is connected to the central upright section of the coils 8. The union 6 is connected by the pipe 9 to the central section of coils 8, the said coils are heated by a burner 10 located in the lower end of the casing 1 and is supplied with gas through the pipe 11. The cold water is supplied 35 through the pipe 12 to the coils 8, said cold

water pipe being provided with a sediment cock 13, a check valve 14 and a valve 15 to cut off the water supply. The cold water passes through the pipe 12 and enters the coils 8 where it is heated and passes through 45 the pipe 7 and pipes 8 to the radiator sections 2. The return water runs back to the pipe 12 and is again heated. The case 1 is provided with a door 17 and an opening 18 through which a match may be inserted to 80 light the burner 10. The upper end of the case 1 is provided with an opening over which the pipe 19 fits, the latter being provided with a valve 20 adapted to close the opening 21 or 22. This pipe 19 allows the 55 heat in the case 1 to pass out through the opening 22 at the top to the room in which the radiator is being used, when the valve 20 is in the position shown in Fig. 2, and in summer time or at other times when it is not 60 desired to have the heat in the room the valve is raised to close the opening 22 and allow the heat to pass through the opening 21 to the chimney or outside of the room.

Having thus described my invention, what 65 I claim is:—

In a gas water radiator the combination of a case, a door for said case, radiator sections arranged on opposite sides of said case, a water coil within said case and having a 70 central upright section connected at its upper and lower ends with said radiator sections, a burner in said case to heat said coils, an opening at the upper end of said case, a pipe fitted in the opening at the top of the 75 case and having two openings therein, and a valve to control the openings in said pipe.

In testimony whereof I affix my signature.

JOHN G. MEYER.
